205,392

LEAF FOUNTAIN

Robert Mifsud, 42 Westland Drive, Glen Cove, N.Y.

Filed Oct. 21, 1965, Ser. No. 87,693

Term of patent 14 years

(Cl. D91—4)

FIG. 1 is a perspective view of the leaf fountain of the present invention; and

FIG. 2 is a top view of the leaf fountain of the present invention.

I claim:

The ornamental design for a leaf fountain, as shown.

References Cited by the Examiner

Architectural Record, August 1959, p. 270, fountain at top.

WALLACE R. BURKE, Primary Examiner.

J. PAUL GUERTIN, Assistant Examiner.